UNITED STATES PATENT OFFICE.

WILLARD C. BRINTON, OF NEW YORK, N. Y.

SIPHON.

Application filed March 23, 1922. Serial No. 545,935.

To all whom it may concern:

Be it known that I, WILLARD C. BRINTON, a citizen of the United States, and a resident of New York, county and State of 5 New York, have invented certain new and useful Improvements in Siphons, of which the following is a specification.

My present invention relates to siphons of the automatic or "self-starting" type, and 10 the objects of the invention are to provide a simple, practical and inexpensive device of this character, which will be definite and positive in its action, and which will be particularly suited to the handling of more or 15 less viscous liquids such as cream and milk.

The special novel features of the invention which make possible the attainment of the above objects will be clear from the following specification which is to be read 20 in conjunction with the drawing accompanying and forming part of the same.

In the drawing referred to Figure 1 is a vertical sectional view illustrating one of the practical embodiments of the invention 25 as in use for removing the cream from the top of a bottle of milk.

Figure 2 is a broken enlarged sectional view illustrating a method of securing the air compressing chamber on the end of the 30 siphon tube.

Figure 3 is a fragmentary view indicating in a general way the functioning of the contracted throat.

Figure 4 is a broken sectional view of a 35 slightly modified form of the invention.

In this invention the siphonic action is initiated by the air trapped within an air compressing chamber or bell 5 carried by and surrounding the intake leg of the 40 siphon, such chamber being in communication with the siphon by a restricted opening 6. The air thus trapped upon the lowering of the siphon into the liquid, passes up through the column of liquid in the tube, in the form 45 of bubbles which carry with them, enough liquid to start the siphonic flow.

This action naturally varies to a certain extent in accordance with the viscosity of the liquid, the operation being delayed, or 50 in some instances, less certain, with the heavier and more viscous liquids.

To overcome this possible fault or uncertainty, I provide in the discharge leg of the siphon a restriction or contraction which 55 will have a tendency to concentrate the

liquid carried over by the bubbles into a unitary mass or globule which will completely fill up the tube and hence form a liquid piston which, subjected to the action of gravity at the discharge side of the siphon, will then act in the nature of a piston, in its fall down the relatively long discharge side of the siphon, to create the suction necessary to positively start the siphonic flow.

In the first form of the invention disclosed this reduction is accomplished by swaging the discharge side of the tube to a lesser diameter, commencing at the point 7, just over the peak of the bend or arch in the 70 tube, this reduced diameter continuing clear to the discharge mouth of the tube so that the liquid plug will have no chance for expansion and will therefore operate as a close-fitting piston during its entire descent. 75 While I have described only the action of this first formed plug or piston, it will be realized that others may form behind this first piston, before the solid flow of liquid commences.

In some instances, for example, for handling certain liquids it may be desirable to keep the full or substantially the full diameter in the discharge side of the tube and to have the contraction only at the one 85 point in the tube, for instance, as I have indicated at 8 in Figure 4. Here the contraction is reduced by simply rolling or indenting a groove in the exterior of the tube so as to produce an internal contraction. 90 With this construction the operation will be substantially the same as described, except that the action will be more like that of an injector or aspirator, rather than a simple piston.

As a further means of making the action more definite and certain I may expand the intake end of the siphon tube into a funnel or bell-mouth such as indicated at 9. This 95 operates as a collector, as the siphon is lowered in the liquid, causing the column of liquid to rise with considerable force and possess a degree of momentum or kinetic energy at the time it is acted upon by the bubbles, which therefore operate the more effectively.

The air compressing chamber may be secured upon the tube in various ways, for instance, by knurling longitudinal ribs 10 on the wall of the tube, and then forcing the 110

sleeve portion 11 of the bell or cup over these ribs, which preferably are of less length than the sleeve, as indicated in Figure 2, so as to leave an amount of solid or uncut material 5 12 at the lower end of the sleeve. The upper end of the sleeve, which has been cut to a certain extent in the forcing of the sleeve over the tube may be swaged inward into close-fitting engagement with the tube 10 and over the upper ends of the ribs, as indicated at 13. This method of fastening, it will be seen, locks the bell against longitudinal movement in either direction and also secures the bell against rotative movement 15 on the tube. When the parts are fastened in this way, the funnel on the end of the tube may be formed after the bell has been secured in place.

It will be seen from the foregoing that my 20 invention provides a simple and practical means for adapting the siphon to the handling of the more viscous liquids and makes it particularly useful and desirable for the purpose of removing the cream from the top 25 of milk and the like.

What I claim is:

1. A self-starting siphon having an air trapping chamber connected with the intake side thereof and provided with a liquid concentrating throat in the discharge side thereof, consisting of an abrupt contraction in the siphon tube located relatively close to the peak in the bend of the tube and at the discharge side of said peak.
2. The structure of claim 1 in which the discharge side of the tube is of the same reduced internal diameter from the contraction therein to the end of the tube.
3. A self-starting siphon having an air

trapping chamber connected with the intake 40 side thereof and having an outlet leg restricted in internal diameter substantially throughout its length, the diameter of the restricted portion of the outlet leg being less than the diameter of any portion of the intake leg.

4. A self-starting siphon consisting of a cylindrical tube having the major portion of its outlet leg of less diameter than the 50 inlet leg thereof and means associated with the inlet leg and operable by the insertion of the inlet leg in the liquid for initiating the flow of liquid.

5. A self-starting siphon consisting of a cylindrical tube having the major portion of its outlet leg of less diameter than any portion of the inlet leg thereof and means including an open ended bell associated with the inlet end for initiating the flow of 55 liquid.

6. A self-starting siphon comprising a tube having a concentric air trapping bell on the intake end thereof with a restricted opening from said bell into the tube, said tube having a contracted throat in the discharge side thereof at a point relatively 60 close to the bend or arch in the tube.

7. A siphon tube having substantially longitudinal ribs formed thereon and an air trapping bell having a sleeve portion surrounding the ribbed part of the tube and having the opposite ends of the same closed over the opposite ends of the ribs aforesaid.

In witness whereof, I have hereunto set my hand this 22d day of March, 1922.

WILLARD C. BRINTON.
